UNITED STATES PATENT OFFICE.

WILLIAM L. SCHMIDT, OF EASTON, PENNSYLVANIA, ASSIGNOR OF ONE-HALF TO WILLIAM S. BROTMAN, OF EASTON, PENNSYLVANIA.

RHEOSTAT.

SPECIFICATION forming part of Letters Patent No. 777,439, dated December 13, 1904.

Application filed June 7, 1904. Serial No. 211,546. (No model.)

To all whom it may concern:

Be it known that I, WILLIAM L. SCHMIDT, a citizen of the United States, residing at Easton, in the county of Northampton and State of Pennsylvania, have invented new and useful Improvements in Rheostats, of which the following is a specification.

This invention relates to an improved form of rheostat and comprises two co-operating cylinders or winding-drums, one of which is composed of non-conducting material, while the other is made of conducting material, said drums being moved relatively to each other to transfer a known resistance of wire which is unwound from one drum in any number of turns or convolutions to be simultaneously wound or wrapped upon the other to thereby include or withdraw the same from the circuit to be varied, which introduction or withdrawal of resistance is accomplished without sparking, and permitting any resistance desired between certain minimum and maximum limits.

In the accompanying drawings, Figure 1 represents a front elevation of the rheostat. Fig. 2 represents a sectional view thereof.

Like numerals of reference indicate like parts in both figures.

Referring to the drawings by numerals, 5 represents the casing or housing of the rheostat, the general shape of which is rectangular. This casing has front and rear walls or plates 6 and 7. These walls or plates are preferably made of light castings and are provided with openings 8, 9, and 10 for purposes to be hereinafter described. The plates are connected to each other by rods 11 and 12, which extend in parallelism, as shown. The side walls 13 of the casing are preferably 40 formed of an enveloping sheet of wire-screen to provide for ventilation, and thereby allow of the radiation of any heat as soon as it is generated by the resistance-coils within the casing. Within the casing thus constructed 45 are arranged winding-drums 14 and 15, that are mounted in operative relation to each other, respectively, on shafts 16 and 17, which latter are mounted for rotation in the journal-openings 8 and 10, located, respectively, in the front and rear plates 6 and 7. 50

Mounted concentrically on the projecting end of the shaft 16, which carries the drum 15, is the gear-wheel 18, which is adapted to engage and mesh with the pinion gear-wheel 19, that is mounted for rotation on the projecting end of the stub-shaft 20, arranged in parallelism with the adjacent end of said shaft 16. Mounted on the stub-shaft 21 is the master driving gear-wheel 22, which is adapted to engage and mesh with the pinion 19, 60 and which is adapted to be manually operated by reason of the handle 23, keyed to the projecting end of said shaft. The outer projecting end of the shaft 17 is likewise provided with a driven gear 24, that is adapted 65 to engage and mesh with the driving-gear 22. It will be observed that by this train of gears both drums may be simultaneously revolved in opposite directions by a turn of the operating-handle in a given direction, and thereby serve to reel or wind the resistance-wire to be transferred from one to the other, as desired. It will also be seen that by such an arrangement of gearing and the relative sizes or ratios of same by one complete turn 70 of the operating-handle the drums may be caused to rotate several times to cause the complete transfer of the wire from one to the other of said drums according to the direction in which said handle is turned. Another advantage which is derived from the arrangement of the gears and the moving parts in the manner shown and described is that they are brought into proper and close relationship in front of the machine, where they may 75 be inclosed by the front plate 25, which is secured, as shown, by the stud-bolts 26.

I will now proceed to describe the special construction of the respective winding-drums.

The drum or cylinder 14 is composed of conducting material, such as aluminium-bronze, and is preferably shown as being made up of a series of cylindrical castings or disks 27, that are rendered rigid by means of the rims or flanges 27' and which are mounted on said 85 shaft 17 in a manner to have a common axis 90

95

- of rotation and which are insulated therefrom and from each other. These disks are provided on their peripheral faces with spiral grooves 28, that are left-handed in direction, 5 as shown, and which are adapted to serve as guides for the strands or convolutions of wire to be wound thereon. This constitutes one member of the winding and transferring pair. By constructing the conducting cylinder or 10 drum in sections or disks, as shown, the number of coils of resistance-wires may be multiplied correspondingly, whereby a given resistance may be transferred one way or the other more quickly.
- 15 15 represents the opposite cooperating drum or member of the winding pair, which comprises an elongated hollow cylinder of non-conducting material, such as porcelain, the peripheral plane of which coincides with that 20 of the drum 14 and which is grooved spirally in a right-handed direction on the said periphery by guiding-grooves 28', that are arranged in operative alinement with the grooves located on the opposite winding-drum.
- 25 29 indicates the resistance-wire of the coils wound about the respective drums. This wire to be suitable for such a purpose should be of the highest specific resistance and should be of such material as will change the least with 30 changes of temperature, and this resistance-wire may be of elastic braided form or twisted and composed of several small wires. 30 and 31 indicate annular strips which are respectively mounted on the rear end or face 35 of said drum in concentric relation and which constitute the movable contact-terminals of the drum-carried circuit to be presently described. From the contact-strip 30 one branch of the said drum-carried circuit leads 40 longitudinally through said drum in a manner to be concealed in one unbroken strand of wire 32, insulated as shown. The branch forming the circuits return to the contact strip or terminal 31. This latter branch is 45 composed of broken lengths 33, threaded through drill-holes 34 to form bends, as shown, in a manner to provide a wire reinforce and present a longitudinally-extending series of properly-spaced circuit-loop members, the 50 ends 35 of which project into the plane of the grooved periphery of said drum which is adjacent thereto and which are connected, respectively, with the wire ends of the respective coils of wire 36, which are arranged 55 in a series corresponding to the disks upon which they are normally wound and by reason of the successive electrical connection of said loops with said disks by the cross connecting-wires of the respective coils are brought into 60 operative serial connection with each other to complete the return branch of the drum-carried circuit to its terminal or contact strip 31. From this arrangement it will be observed that the smallest fractional part of the resistance material or wire transferred from the 65

one drum to the other changes the current passing through said circuit correspondingly and that the resistance may be introduced and withdrawn without sparking and that by the complete unwinding of every convolution of 70 wire from the said drum 15 and its transference to the drum 14 there is still left a return branch circuit, which is completed by reason of the alternate connections of the loops and the disks through the wire 29 of the coils 36 75 in succession throughout the entire series to the contact-strip 31.

37 and 38 indicate the binding-posts, which serve to form the terminals of the external circuit and their connection with the partial 80 circuit carried by rheostat. Each binding-post is shown as being adapted to be removably attached to the thimble 39, which extends through the rear plate and which is interiorly threaded and which is provided with a spring 85 40, which abuts or shoulders at one end against the inner projecting end of said post and with its opposite end against a bearing-button 41, projecting inwardly against the adjacent contact-strip carried by the drum 15. 90

Having thus described my invention, what I claim is—

1. In a rheostat the combination of a pair of oppositely-turning winding-drums, one of which is composed of non-conducting material, conductors carried by said drums, which may be transferred from one to the other, suitable connections for including an external circuit, and means for bringing into operative relation with said connections only that portion of the wire conductor that is wound about the non-conducting drum, and that extends beyond the limits of the opposite drum member, substantially as described. 100

2. In a rheostat, the combination of a pair of oppositely-turning winding-drums one of which is made of conducting material while the other is made of non-conducting material and which are provided with one or more conductors wound thereon, and which are geared together substantially as described, and suitable cross connections by which said conductors are linked together and put in circuit when wound upon the non-conducting drum, substantially as described. 110

3. In a rheostat, the combination of a pair of oppositely-turning winding-drums, which are provided with a plurality of conductors wound thereon, and which are geared together to be driven at a rapid peripheral speed, substantially as described, one of said drums being made of non-conducting material and provided with peripheral spiral grooves, and carrying a partial circuit made up in one branch thereof by a series of connections, while the other of said drums is made of a series of conducting-disks that are suitably insulated, and that are provided circumferentially with spiral grooves, and that correspond in number with the adjacent series of connections on the op- 120 125 130

posite drum, said disks being adapted to receive the transfer of the conductor wound on the adjacent portion of the opposite drum, without separating the cross connecting-wires 5 of said coils with the connections of the partial circuit, whereby the said partial circuit is at all times complete within said rheostat, substantially as described.

4. In a rheostat, the combination of a pair 10 of oppositely-turning winding-drums, one or more conductors wound thereon, and geared together substantially as described, one of said drums being made of conducting material while the other is provided circumferentially 15 with a facing of non-conducting material, and which carries a partial circuit, that is completed in one of its branches by cross connections at intervals with the oppositely-arranged conducting-drum, said partial circuits terminating 20 in contacts and binding-posts arranged, respectively, in sliding contact with the drum-carried contacts, substantially as described.

5. In a rheostat, the combination of an inclosing case having ventilative openings, horizontal 25 rotary shafts mounted in parallelism therein, and geared together to be rotated in

opposite directions, drums mounted to rotate on the respective shafts, and arranged to present their peripheries in proximity and in a given plane, one of said drums being made of 30 non-conducting material, and provided on its periphery with right-handed spiral grooves, while the other of said drums is made of conducting material and provided circumferentially with left-handed spiral grooves arranged 35 in operative alignment with those of the opposite drum, wire conductors carried by said drums, which may be transferred by winding from one to the other, suitable connections for including an external circuit; and means 40 for cutting in circuit only that portion of the wire conductors that is wound about the non-conducting drum and that extends beyond the limits of the drum member, substantially as described. 45

In testimony whereof I affix my signature in presence of two witnesses.

WILLIAM L. SCHMIDT.
